ATTORNEYS

UNITED STATES PATENT OFFICE.

ELMER LOVELL SMITH, OF SPRINGFIELD, MASSACHUSETTS, ASSIGNOR TO PACKAGE MACHINERY COMPANY, OF SPRINGFIELD, MASSACHUSETTS, A CORPORATION OF MASSACHUSETTS.

WRAPPING MACHINE.

Application filed November 15, 1921. Serial No. 515,263.

To all whom it may concern:

Be it known that I, ELMER LOVELL SMITH, a citizen of the United States, residing at Springfield, in the county of Hampden and 5 State of Massachusetts, have invented new and useful Improvements in Wrapping Machines, of which the following is a specification.

The present invention relates to improvements in wrapping machines and more particularly to machines wherein an article is completely enclosed within a sealed wrapper. Although capable of more general application, the invention is especially useful 10 for wrapping relatively small rectangular articles such as cakes of dry or hard yeast.

In order to properly preserve cakes of dry yeast, it is essential that the individual cakes shall be carefully wrapped in such a 20 manner as to insure their adequate protection from air and moisture. It has been difficult heretofore, however, to wrap the yeast in a uniformly efficient and reliable manner by reason of the fact that the cakes 25 vary more or less in size because of different conditions to which they are subjected while drying.

One object of the present invention is to provide an improved machine which will operate to tightly and carefully wrap solid rectangular articles such as individual cakes of dry yeast, and to seal the wrapper effectively and reliably irrespective of slight variations in the size of the articles.

Another object of the invention is to provide, in a machine for wrapping articles which may vary from one another slightly in size, means operative irrespective of such variation for centrally locating the articles 35 relatively to two opposite edges of the wrapper which is to be applied thereto.

Another object of the present invention is to provide, in a wrapping machine of the character described, means for operating 45 upon the articles prior to the wrapping thereof to insure the removal therefrom of undesirable projecting edges or fins which may be present upon certain sides or faces of the articles.

A further object is to provide in a wrapping machine generally improved mechanical structure.

With these and other objects in view, as

will hereinafter appear, the invention consists in the features of construction and in 55 the combinations and arrangements of parts set forth in the following description and particularly defined in the appended claims.

The invention will be best understood from a description of the preferred embodiment thereof illustrated in the accompanying drawings, in which:

Fig. 1 is a side elevational view of a machine embodying the invention;

Fig. 2 is a sectional plan view thereof, 65 taken substantially on the line 2—2 of Fig. 1;

Figs. 3, 4 and 5 are detail sectional views taken on the lines 3—3, 4—4, and 5—5, respectively, of Fig. 1;

Fig. 6 is a detail plan view of a portion of the device for cooling the folded over wrapper ends after they have been sealed by the application of heat thereto;

Fig. 7 is a sectional detail view showing 75 portions of the positioning or centering device for locating the articles relatively to their wrappers and showing also the trimming knives associated with said positioning device;

Fig. 8 is a perspective view of one of the arms of the article positioning device showing particularly the mounting of the trimming knife;

Fig. 9 is a perspective view of a cake of 85 dry yeast illustrating particularly the projecting edges or fins that are removed by the trimming knives;

Figs. 10 to 16, inclusive, are perspective views illustrative of different stages in the 90 operation of wrapping an article;

Fig. 17 is a detail elevational view of a portion of the actuating mechanism for the arms which function in the feeding of the articles into the rotatable turrets and which 95 remove the articles therefrom;

Fig. 18 is a perspective view of a portion of the folding chute; and

Fig. 19 is a detail view, in end elevation, of a portion of the folding chute illustrating 100 its action upon a partially wrapped article.

The particular machine shown in the drawings is constructed and arranged to wrap cakes of dry or hard yeast which are of the usual rectangular shape having two 105 square faces and four relatively narrow

faces. The yeast cakes lie flat, i. e., with their square faces horizontally disposed, throughout a considerable portion of their travel through the machine, but at certain 5 times they are inverted with respect to their positions at other times. The square faces of the articles will therefore, for convenience of description, be hereinafter designated "top" and "bottom" faces with reference to 10 the position of the article at the particular time in question. Also the four narrow faces will hereinafter be described with reference to the direction of travel of the article at the particular time when said faces 15 are mentioned. Accordingly, the narrow face which is foremost in the direction of feed of the article will be designated the "front" face, the face opposite thereto will be termed the "rear" face, and the two remaining narrow faces will be referred to as 20 the "end" faces of the article. Furthermore, portions of the wrapper extending beyond the front or rear faces of the articles will be termed the "end" extensions, while portions 25 of the wrapper projecting beyond the end faces of the article will be referred to as the "side" or "tubular" extensions of the wrapper.

The invention contemplates the use in connection with the present machine of wrapping material which has been previously treated with wax, or like substance, in order that the wrappers may be sealed and made air-tight by heating the overlapping portions thereof to soften or melt the wax in the wrapper material and then allowing the same to cool and solidify.

The machine will first be more or less briefly described in connection with the various operations which it is adapted to perform. Referring to the drawings, the articles or yeast cakes A are supplied, square face down and one behind another, upon an endless belt conveyer 20 which extends 40 transversely of the machine. The conveyer 20 feeds the articles into the path of a pusher 22 which reciprocates horizontally at right angles to the length of the conveyer. The pusher 22 removes the articles singly from 45 the conveyer 20 and advances them toward a vertically disposed wrapper W, and between the arms of a positioning device 26 which locates them centrally with respect to the vertical edges of the wrapper. The 50 continued advance of the pusher 22 then forces the wrapper and article together into one of the pockets of a turret or tumble box 28, the latter being intermittently rotatable and being positioned, during its intervals of rest, with one of its pockets located at an article receiving station 30 while another pocket is positioned at a delivery 55 station 32. The introduction of the article and wrapper into the pocket of the tumble box causes the wrapper to be laid in U-form

about the front, top and bottom faces of the article. Just before the article enters the pocket in the tumble box 28, the wrapper W engages a yielding plate 34 carried by an arm 36 which thereafter advances in 70 unison with the pusher. The arm 36 enters the pocket of the tumble box ahead of the article and the yielding plate 34 prevents displacement of the wrapper by holding it firmly against the forward edge of the article. The wrapper is so positioned, when engaged by the advancing article, that when the wrapper is carried into the tumble box the top face of the article will be only partially covered by the wrapper, as shown at a 80 in Fig. 10, whereas the front and bottom faces of the article will be entirely covered thereby and the wrapper will extend rearwardly beyond said bottom face, as indicated at b in Fig. 10, in order that the rear end extension of the wrapper may subsequently be folded over what is now the rear face and over a portion of what is now the top face of the article in overlapping relation with that portion of the wrapper previously laid upon said face. The rearward extension b 85 of the wrapper is laid over the rear face of the article, during the rotation of the tumble box, by an arcuate shield 38 which encircles substantially the lower half of the periphery of the tumble box. After the tumble box has been rotated through one half of a revolution, the article is located in inverted position at the delivery station 32 and appears as shown in Fig. 11, the wrapper extension b being yieldingly held between the periphery of the tumble box and the end of the shield 38 which is adjacent the delivery station. The article is ejected from the tumble 90 box by means of a pusher 40 which pushes the article into a folding chute indicated in whole as 42, during which movement the wrapper extension b is laid against what is then the bottom face of the article, said extension overlapping the portion a of the wrapper as shown in Fig. 12. During the 95 last described movement of the article, the rear side extensions c of the wrapper are folded down against the opposite end faces of the article by the pusher 40 itself, while the forward side extensions d are laid against said ends faces of the article by the action of the folding chute 42, all as shown in Fig. 14. The folding chute 42 also operates to start the folding of the lower side extensions e as shown in Fig. 15. While the article is in the folding chute, the overlapping portions a and b of the wrapper at the bottom of the article are sealed by means of heat supplied to the bottom of the folding chute. The article remains in the folding chute until the tumble box has made another partial rotation, bringing another partially wrapped article into position at the delivery station 32. Upon the ejection 100

of the last mentioned article from the tumble box, the article in the folding chute is ejected from the chute and is introduced into one of the pockets of an intermittently rotatable 5 turret or carrier 44 while said pocket is located at a receiving station 46. As the article is advanced into the pocket of the turret 44 it passes between a pair of heater plates 48 which are constructed and arranged to 10 complete the folding of the lower end extensions *e* during the passage of the article therebetween. The article now appears as shown in Fig. 16. The upper end extensions *f* are now the only portions of the 15 wrapper remaining unfolded and these extensions project into narrow channels in the heater plates. As the turret 44 starts to rotate, the extensions *f* are pulled out of the channels in the heater plates and the upper 20 edges of these plates operate as the turret 44 rotates to fold said extensions down against the article, overlapping the extensions *e* and to heat-seal said overlapping portions. The articles are now completely 25 wrapped and they are moved by the intermittent rotation of the turret 44 between the oppositely disposed members of a cooling device 50, said device operating to hold the folded wrapper extensions in place and 30 under a slight yielding pressure as they are moved away from the receiving station, and also to extract heat from the wrapper so that the wax will set and the wrappers will be permanently and effectively sealed before 35 leaving the machine. The rotation of the turret 44 finally brings the wrapped and sealed articles to a delivery station 52 when they are ejected from the turret 44 by means of a pusher 54.

40 The greater part of the driving mechanism of the machine is located between two spaced vertical side frames 60 rising from a bed 62 supported by a pedestal 64, and the various instrumentalities which operate 45 upon the articles are mounted adjacent the outer face of the side frame 60, at the front of the machine. A main drive shaft, (not shown) may be journaled in the pedestal 64 and this shaft may derive its power from 50 any suitable source and is connected, through a chain 66 and suitable sprockets, with a horizontal cam shaft 68 (Fig. 1). The cam shaft 68 drives, through a chain 70 and suitable sprockets, a horizontal shaft 72, and the latter is connected by any suitable 55 means, such as intermeshing gears (not shown) with a shaft 74 which is the driving shaft for the wrapper feeding mechanism. The shafts 68, 72 and 74, together with driving 60 shafts 76 and 78 for the turrets 28 and 44, and a rock shaft 79 are journaled in bearings in the side frames 60. The turret shafts 76 and 78 extend beyond the front side frame to receive and support their respective turrets which are rigidly secured

thereto, and the turret shaft 76 and the shaft 72 project beyond the rear side frame. On the rearwardly projecting end of the shaft 72 is secured a crank 80 which operates a Geneva cam or star wheel 82 secured to 70 a short horizontal shaft 84 that is journaled in the rear side frame. The shaft 84 drives, through intermeshing gears 86, the turret shaft 76, and through a chain 88 and suitable sprockets said shaft also drives the 75 other turret shaft 78. The design of the Geneva cam and the ratio of the above described driving connections between the shaft 84 and the two turret shafts 76 and 80 80 is such that the turret 28 will be rotated through one quarter of a revolution at each cycle of operations of the machine while during the same cycle the turret 44 will be rotated through one tenth of a revolution. The direction of rotation of each turret is 85 indicated by arrows in Fig. 1.

The turret or tumble box 28 is of peculiar construction, having its outer peripheral portion disposed in a plane axially offset from its inner portion, so as to afford an 90 annular recess 90 (Fig. 2). In the outer peripheral portion of the turret 28 are four equally spaced radial slots 92 which constitute the article receiving pockets and which extend further than necessary for this purpose to communicate with the recess 90. Rigidly secured to one side wall of each 95 radial slot 92 is a plate 94 while a corresponding plate 96 is yieldingly mounted adjacent the opposite side wall of each slot. The plates 94 and 96, thus form the opposite 100 side walls of the pockets for receiving the articles and wrappers. As shown, the yielding plates 96 are acted upon by suitable springs 98 carried by the turret and are supported for yielding movement in planes parallel to the fixed plates 94 by means of pins 99 that are suitably supported and guided in the turret. Inasmuch as the turret 28 is intermittently rotated through quarter revolutions, as described, the article receiving pockets 92 are successively brought to rest at the receiving station 30 for the reception of an article and its wrapper, and concurrently with the arrival of a pocket at the receiving station another pocket at the opposite side of the turret is positioned at the delivery station 32 for the discharge of its article therefrom. Both plates 94 and 96 are grooved to provide narrow parallel ribs 110 115 120 125 95 (Fig. 2) extending in the direction of movement of the articles as they are introduced into the pockets or ejected therefrom. This construction reduces any tendency which the partially wrapped articles may have to stick to the sides of the pockets.

Cooperating with the turret 28 are the arms 36 and 40 which reciprocate in the horizontal plane of the axis of the turret. During each period of rest of the turret, the 130

arm 36 moves inwardly through the pocket 92, which is positioned at the receiving station 30, and into the annular recess 90 where it remains while a quarter rotation is imparted to the turret to advance the article toward the delivery station 32 and to bring an empty article receiving pocket to the receiving station 30. Upon the arrival at the receiving station of the empty pocket 92 10 the arm 36 moves outwardly through this pocket into position to be engaged by a new article in order that it may precede the same as it is introduced into said pocket. The arm 40 operates at each interval of rest of 15 the turret to remove a partially wrapped article from the pocket 92 which is positioned at the delivery station 32 and to introduce said article into the folding chute 42. To this end, the arm 40 is located within 20 the annular recess 90 during the movement of the turret and moves outwardly through the pocket at the delivery station as the turret comes to rest after each step movement thereof. Before the turret again starts to 25 rotate the arm 40 returns to its normal position within the recess 90 so that it will be ready to transfer the next article from the turret 28 to the folding chute 42.

The turret or carrier 44 is, in a general 30 way, similar in construction to the turret 28, just described, except that the turret 44 is provided with ten radial, equally spaced article receiving pockets instead of four such pockets as in the turret 28. The 35 pockets in the turret 44 are indicated at 100 and a central annular recess with which said pockets communicate, is indicated at 102. At each cycle of operations of the machine, one of the pockets 100 is moved 40 into a position of rest at the receiving station 48 while the pocket diametrically opposite thereto is positioned at the delivery station 52. At each period of rest of the 45 turret 44 an incompletely wrapped article is transferred from the folding chute 42 to an empty pocket 100 at the receiving station 48, while at the same time a completely wrapped and sealed article is ejected from the pocket at the delivery station 52 by 50 means of the arm 54. The ejector arm 54 is normally positioned in the annular recess 102 and is connected to operate in unison with the arm 40 already described. Accordingly, at each cycle of operations the 55 arm 54 moves outwardly through the pocket at the discharge station 52 to eject an article from the pocket and the arm is then retracted through the same pocket into the recess 102 before the turret again rotates.

60 The arm 36 extends at right angles to an upright bar 104 (Figs. 2 and 17) to which it is rigidly secured and which is, in turn, fixed to a horizontal rod 106 and slidably receives a second parallel rod 108 which is 65 located above the rod 106. The rods 106

and 108 are slidably mounted in brackets 110 on the front side frame 60. The arm 40 is fixed to an upright bar 112 which is rigidly secured to the upper rod 108 and slidably receives the lower rod 106. The arm 54 is secured to the upper rod 108. The three arms 36, 40 and 54 lie in the common axial plane of the turrets 28 and 44 and extend forwardly into the path of the articles that are being wrapped. The lower rod 106, 75 and with it the arm 36, are reciprocated by means of a cam lever 114 which is loosely mounted on the rock shaft 79, said lever being connected by a link 116 with the bar 104, and carrying a cam roll 118 which rides in a groove in a cam disk 120 on the cam shaft 68. The upper rod 108, and with it the arms 40 and 54, are reciprocated by means of a cam lever 122 which is also loosely mounted on the rock shaft 79, said 80 lever being connected by a link 124 with the bar 112 and carrying a cam roll 126 which rides in a cam 128 on the cam shaft 68. The grooves in the cams 120 and 128 are designed to move the arms 36, 40 and 54 85 in the time relation to the cycle of operations already set forth.

The conveyer belt 20, by means of which the articles are fed into the path of the pusher 22, passes over suitable pulleys, one 90 of which is shown at 130, and the upper stretch of the belt is supported by a bar 132 one end of which is secured to the front side frame 60. The articles travel along with the belt 20 between suitable side guides 100 134 and as they are advanced into the path of the pusher 22 they pass beneath a horizontal plate 136 which is supported from the front side frame 60 and prevents upward displacement of the article while the latter 105 is being transferred by the pusher 22 from the conveyer belt to the turret 28. The foremost article on the belt 20 is arrested by means of an abutment 138 (Fig. 2) when it has reached a position in front of the pusher 110 22. The abutment 138 may conveniently be secured to the under side of the plate 136. The belt pulley 130 is fixed upon a shaft 139 rotatably supported upon the front side frame 60. The shaft 139 is driven from the 115 cam shaft 68 through intermeshing spiral gears 140.

The wrapper feeding mechanism may be of any suitable type, that shown for purposes of illustration being substantially the same in construction and mode of operation as that disclosed in United States Letters Patent No. 1,330,854, granted Feb. 10, 1920 to the present applicant. It is not, therefore, considered necessary to describe the illustrated wrapper feeding mechanism in detail herein, since reference may be had to said patent for a thorough understanding of the wrapper feeding operation. Briefly described, however, the wrapping material 125 130

is drawn, in strip form, from a roll 142 and between unwinding rolls 143 by means of feed rolls 144 one of which is fixed to the driving shaft 74. The wrapper strip is fed 5 by the rolls 144 between the cooperating members of a shearing device 146 which is actuated from the feed roll shaft 74 in such timed relation as to sever an individual wrapper W from the strip when a piece of 10 the required length has been fed beyond the shear members.

After passing beyond the shearing device 146 the leading end of the strip of wrapper material is fed through a slot 148 in the 15 horizontal plate 136 and into a wrapper receiving pocket 150 (Fig. 1) in which the individual wrappers, are supported in a vertical position after being severed from the wrapper strip. To guide the leading end 20 of the wrapper strip into the slot 148, a pair of flaring side guides 152 are secured to the upper face of the plate 136 adjacent the opposite sides of the wrapper receiving slot.

The wrapper receiving pocket 150 is 25 formed between the vertically disposed portion of a bracket 154 and a vertical plate 156, said bracket and plate constituting the opposite sides of said pocket. The bracket 154 is secured to the front side frame 60. The 30 plate 156 is supported from the bracket 154 by means of connecting webs 158, said webs being arranged to constitute the front and rear ends of the pocket 150. Rising from the webs 158 at opposite ends of the pocket 35 150 are edge guides 160 (shown in Fig. 2 and omitted in Fig. 1) which are adapted to engage the vertical edges of the wrapper to guide the wrapper into the pocket. The bottom of the pocket 150 is formed of a 40 wire 162 which depends from the bracket 154 and is bent to support the lower edge of the wrapper and position the wrapper vertically for the first step in the wrapping operation, i. e., the feeding of the forward 45 edge of the article against the wrapper. The vertical plate 156 is provided with a bevelled upper face 164 across which the wrapper is drawn as the article is fed into the pocket of the turret 28.

50 The articles A are fed against the wrapper W and into the turret or tumble box 28 by the pusher 22, the latter being reciprocable in a guideway 166 that is supported by the front side frame 60. The 55 pusher 22 is connected by a link 170 to an arm 172 that is fixed to the rock shaft 79. The rock shaft 79 is actuated from the cam shaft 68. To this end a cam groove (not shown) in the cam disk 120 receives a roll 60 174 carried at one end of a link 176, the opposite end of which is pivotally connected to an arm 178 on the rock shaft 79. The link 176 is provided with a longitudinal slot 180 through which the shaft 68 extends for 65 the purpose of supporting the link, the slot

being long enough to permit the necessary range of movement of the link to produce the desired travel of the pusher 22.

As the articles are removed from the conveyer belt by the pusher 22, they are 70 supported upon a horizontal feed table 182 (Fig. 2) which is formed integrally with the bracket 154 and extends from the conveyer belt to the wrapper pocket 150. While being advanced across the feed table 182, 75 the articles are acted upon by the positioning device 26 which locates them centrally between the vertical edges of the wrapper W, in order that said edges of the wrapper shall overlap to the same extent at opposite 80 faces of the article when folded thereabout.

The positioning device 26 comprises a pair of similar bell crank levers 184 which are disposed in a horizontal plane above the plane of the articles and are severally 85 pivoted upon vertical studs 186 rising from the plate 136. The longer arms of the levers 184, are disposed substantially parallel to each other and extend in the direction of feed of the articles at opposite sides 90 of their path of movement, and depending from the free extremities of these arms are gage members or shoes 188 for engaging the lateral edge faces of the articles. The shorter arms of the levers 184 extend toward each other and are provided with segmental gear teeth 189 which intermesh so that the shoes 188 are constrained to move toward and from each other in unison. The shoes 188 are yieldingly urged toward one 95 another by means of a spring 190 secured at one end to the front side frame 60 and at the other end to a third arm 192 on one of the levers 184. As shown, the limit of approach of the shoes 188 is determined by 100 a stop 194 on the plate 136 which engages the arm 192 and is arranged to enable the shoes 188 to be engaged and spread apart by the articles. The ends of the shoes 188 first engaged by the articles are bevelled, as 105 shown at 196 in Fig. 8 to facilitate the entrance of the articles between the shoes. The pivot studs 186 are so positioned and the levers 184 and shoes 188 so constructed 110 and arranged that when no article is present 115 between the shoes the opposed faces of the latter will be located at equal distances from the adjacent vertical edges of a wrapper which has been positioned in the pocket 150. The corresponding arms of the bell crank 120 levers 184 being of equal length it is obvious that articles will be centered relatively to the vertical edges of the wrapper irrespective of slight variations in the size 125 of the articles.

The cakes of dry yeast upon which the present machine is specifically designed to operate frequently come from the mold in which they are formed with irregular edges or fins projecting from two of their opposite 130

6

narrow faces, as shown at 197 in Fig. 9. It is desirable that these fins be removed before the articles are wrapped in order that the wrapped articles shall be of neat and uniform appearance. For this purpose, trimming knives 198 are carried by the positioning shoes 188. As indicated in Fig. 8, the knives 198 consist of rectangular blocks which are set into the inner faces of the shoes 188. The knives are arranged with their opposed faces and cutting edges 200 flush with the article engaging faces of the shoes so that the knives will not cut into the side faces of the cakes. The rear extremities of the shoes 188 however are narrower than the rest of the shoes and so arranged that portions of the cutting edges 200 of the knives are exposed above and below the shoes. The cakes to be wrapped are supplied to the conveyor 20 in such a way that when advanced by the pusher 22 the fins 197 will extend in the direction of feed of the articles. Thus when the cakes are advanced through the positioning device 26 the fins 197 will project outwardly beyond the planes of the cutting edges 200 and will be trimmed from the cakes thereby leaving the end faces of the cakes of smooth and uniform appearance. It will be seen that the fins will be trimmed by the knives irrespective of whether said fins project from the upper or lower edges of the end faces of the cakes. The fins 197 shown in Fig. 9 have been partially trimmed from the cake, the trimmed edges being shown at 202.

After the article has been centered by the positioning device 26 and while the projecting fins if any were present, are being trimmed therefrom by the trimming knives 198, the front face of the article engages the wrapper W and carries it against the yielding plate 34. The cam groove which receives the cam roll 174 is so arranged relatively to the other cam groove in the disk 120 that the pusher 22 is advanced to engage an article A, and carry it across the feed table 182 and against the wrapper W prior to the inward movement of the arm 36. The arm 36 commences its inward movement only after the yielding plate 34 has been moved slightly toward said arm by the article and then the pusher 22 and the arm 36 travel in unison until the article has been positioned in its pocket in the turret. Thereafter the pusher 22 draws back into the illustrated position and remains there until the turret again comes to rest. The arm 36, however, continues its inward movement until it becomes located in the annular recess 90 where it dwells during the succeeding partial rotation of the turret, and when the turret again comes to rest the arm 36 returns to its illustrated position through the empty pocket then positioned

at the receiving station. Shortly after the article is advanced beyond the feed table 182 its forward edge engages the yielding plate 34, and presses it towards its supporting arm 36 before the latter arm starts to move toward the turret. Thus the article is held between the yielding plate 34 and the pusher 22 and there is no tendency for its forward portion to tilt downwardly out of its horizontal plane as it passes through the space intervening between the feed table 182 and the turret 28. After the article has engaged the wrapper and while the latter is being carried forward with the article into the pocket of the turret in a well known manner, the wrapper is drawn through the slot in the horizontal plate 136 and across the bevelled face 164 on the vertical plate 156. The article is frictionally held in the pocket between the rigid plate 94 and the spring-pressed plate 96, each of these plates being somewhat bevelled at their outer ends to facilitate the entrance of the article into the pocket. The lower end of the wrapper is not completely withdrawn from the pocket by the movement of the article as the latter is introduced into the pocket of the turret but said end of the wrapper extends beyond the article and overlies the bevelled face 164 at the top of the pocket 150.

After the article has been introduced into the pocket of the turret 28 as described, the turret is rotated through a quarter revolution bringing the article to the bottom of the turret and causing the trailing wrapper extension to be withdrawn from the pocket 150 and folded loosely over the previously uncovered rear face of the article by means of the arcuate folder shield 38. At the next step movement of the turret 28 the article is moved into position at the delivery station 32. The article has now been inverted and the rear face last covered by the wrapper is now the front face of the article and a trailing wrapper end b (Fig. 11) extends downwardly from this face between the periphery of the turret and the adjacent end 204 of the folder shield 38.

To insure that the wrapper shall be smoothly and evenly laid over what is now the front face of the article, the folder shield is adapted to exert a tension upon the trailing wrapper extension b as the latter is engaged by the end 204 of said shield. To this end the folder shield is secured at its lowest point to a rock shaft 206 that is mounted in the front side frame 60 and has an arm 208 fixed thereon adjacent the inner face of said side frame. The arm 208 is acted upon by a spring 210 suitably supported to press the said arm against a stop 212. The stop 212 is so located that the end 204 of the folder shield will be yieldingly positioned, as shown, so as to

cooperate with the peripheral portion of the 5 turret to exert a drag upon the trailing wrapper end *b* as the turret approaches its position of rest and thus cause said wrapper end to be tightly drawn across the front face of the article and held in such condition while the turret remains at rest. As 10 shown in Fig. 1, the end 204 of the folder shield is thickened or reinforced so that it will be more rigid and thus better adapted to perform its wrapper tensioning function. The wrapping of the article has now progressed to the stage illustrated by Fig. 11.

After an article has arrived at the 15 delivery station 32, and while the turret remains at rest, the article is removed from the pocket of the turret and introduced into the folding chute 42 by the action of the feed arm 40. As the article enters the folding chute, the trailing wrapper end remains under tension, being still pressed by the folder shield against the adjacent peripheral portion of the turret, and as a result the wrapper is tightly and smoothly folded over 20 the lower edge of the advancing front face of the article and laid against the bottom face thereof, in overlapping relation with the portion *a* of the wrapper which was first laid against this face of the article.

30 The top, bottom, front and rear faces of the article have now been completely covered by the wrapper and tubular extensions of the latter project beyond the two end faces thereof. As the feed arm 40 advances to transfer the articles from the turret 28 to the folding chute 42, the portions *c* of said tubular side extensions of the wrapper, which project beyond the rear face of the article are engaged by means 35 of spaced folding fingers 214 (Figs. 2 and 12) on said feed arm and folded thereby against the adjacent edge faces of the article, as shown in Fig. 13. The feed arm 40 is also provided with depending 40 prongs 216 which move in the grooves that are formed between the ribs 95 of the plate 94. These prongs 216 back up the portion 45 of the wrapper which covers the lower edge of the rear face of the article and prevents 50 said portion from wedging between the feed arm 40 and the plate 94. Thus said portion of the wrapper is held in close contact with the article and the portion of the wrapper which extends beneath the article 55 is prevented from slipping rearwardly relatively to the article as the latter advances over the ribbed face of the plate 94. This insures that the wrapper will fit tightly over the lower rear corner of the 60 article and also that it will lie smoothly upon the bottom face thereof.

The folding chute 42 (as shown in Figs. 1 and 3) comprises lower and upper horizontal plates 220 and 222, respectively, and 65 opposed side members 224. At the entrance

end of the folding chute, the lower plate 220 is pivotally mounted by means of a horizontal stud 226 projecting from a web 228 formed upon an arm 230 which extends at right angles to the plane of the web and is secured to a bracket 232 which is, in turn, secured to the front side frame 60. The opposite end of the plate 220 is supported from the arm 230 with provision for vertical yielding movement. For this 70 purpose a rod 233 is pivoted to the under side of the plate 220 and extends downwardly through the arm 230. A spring 234 which is coiled around the rod 233 between said plate and arm urges the delivery 75 end of the plate 220 upwardly and holds it yieldingly in a position determined by a stop nut 236 on the lower end of the rod 233 said nut engaging the arm 230 and adapted to be turned to vary the adjustment of the plate. At its rear extremity, the plate 220 is provided with notches 237 (Fig. 18) to receive the ribs 216 on the under side of the feed arm 40 to permit 80 said feed arm to advance to a position 85 slightly overlapping the lower plate 220 of the folding chute.

The upper plate 222 of the folding chute is carried by an arm 238 which is pivoted at 240 to the bracket 232. The supporting arm 238 is normally locked in a horizontal position, as shown in Fig. 3, for the purpose of maintaining the plate 222 in operative relation to the other members of the folding chute, but the arm 238 is adapted 90 to be swung upwardly to raise the plate 222 for the purpose of permitting the removal from the folding chute of an article which may accidentally have become jammed 95 therein. To this end the arm 238 is provided with a spring-pressed detent 242 which is adapted to cooperate with notches 244 in a segmental portion of the bracket 232. When the detent 242 is engaged in the lowermost of the notches 244, as shown 100 in Fig. 3, the plate 222 is operatively positioned. The detent 242 has a suitable handle 246 connected therewith which may be grasped for the purpose of withdrawing the detent from the lower notch. By swinging the arm 238 upwardly until said detent 105 snaps into the upper notch 244, the plate 222 will be latched in its inoperative position and the folding chute will be opened. The plate 222 is pivotally mounted for 110 vertical tilting adjustment upon the arm 238 by means of a pivot stud 243 extending through upturned ears on said plate and through a lug 241 depending from a portion of the arm 238. At the entrance end 115 of the folding chute the plate 222 is yieldingly supported from the arm 238 by means of a rod 242 which is pivoted to the upper side of said plate and extends upwardly 120 through a lug 245 projecting from said 125 plate. At the entrance end of the folding chute the plate 222 is yieldingly supported from the arm 238 by means of a rod 242 which is pivoted to the upper side of said plate and extends upwardly 130 through a lug 245 projecting from said

arm. A spring 248 surrounds the rod 242 between the plate 222 and arm and yieldingly presses said plate toward the lower plate 220. A nut 250, threaded upon the 5 upper end of the rod 242, engages the lug 245 to limit the downward movement of the plate 222. The two plates 220 and 222 are normally spaced apart so as to yieldingly engage the top and bottom faces of 10 the thinnest articles which may be supplied to the machine. The plate 222 flares upwardly at the end nearer the turret 28, as shown at 252, to facilitate the entrance of articles into the folding chute. The 15 above described construction and arrangement of the plates 220 and 222 permits them to automatically adjust themselves relatively to each other to accommodate articles of different thicknesses. It will be seen that the 20 lower plate 220 is unyieldingly supported at the entrance end of the chute and is positioned so as to be in alinement with the rigid plates 94 of the turret pockets when the pockets are at the delivery station 32, 25 whereas the upper plate 222 is yieldingly supported at the entrance end of the chute to accommodate articles of different widths and to apply pressure to said articles. This construction facilitates the entrance of the 30 articles into the chute inasmuch as only one of the plates in the folding chute has to be displaced to permit the articles to enter the chute.

The side members 224 of the folding chute 35 consist of horizontal bars of substantially the length of the plates 220 and 222 and said bars are interposed between the lateral margins of said plates, the arrangement being such that narrow channels are provided between the side members 224 and both plates 220 and 222 to receive the wrapper extensions 40 *e* and *f* which project beyond the bottom and top faces, respectively, of the opposite sides of the article. The side members 224 45 of the folding chute are mounted to yield outwardly to accommodate articles of varying widths. As best shown in Fig. 3, the side members 224 are carried at the upper extremities of a pair of arms 254 which are 50 pivoted upon horizontal rods 256 extending through the bracket arm 230. As shown, the arms 254 are offset outwardly from the planes of the side members 224 to avoid conflict with the lower plate 220. The arms 55 254 are extended below the pivots 256 and these extensions are apertured to loosely receive the opposite end portions of a horizontal rod 258 the central portion of which extends through the web 228 and is rigidly 60 secured thereto. To yieldingly press the side members 224 toward each other, the downward extensions of the arms 254 are forced outwardly by springs 260 which are coiled around the rod 258 between said extensions and the web 228. The limit of ap-

proach of the side members is determined by means of nuts 262 which are threaded upon the ends of the rod 258 and engage the extensions of the arms 254. The nuts are adjusted to insure that the side members 224 will yieldingly engage the lateral edge faces of the smallest articles which may be supplied to the machine.

When an article is introduced into the folding chute 42 the rear portions of the 75 tubular wrapper extensions have been folded against the side faces of the article, as shown in Fig. 13, while the front, top and bottom portions, *d*, *e* and *f* of the tubular wrapper extensions have not yet been folded but project beyond the end faces of the articles as 80 illustrated in said figure. As the front face of the article enters the folding chute, the bottom portions of the tubular wrapping extensions at opposite ends of the article are 85 folded back against the end faces of the article, as shown in Fig. 14, by means of folding projections 264 (Fig. 18) on the side members 224, leaving only the top and bottom portions *e* and *f* of said tubular side 90 extensions to be folded. As the article progresses through the folding chute, the trailing end portion *b* of the wrapper is withdrawn from between the folder shield 38 and the turret and is laid against the opposite 95 end portion *a* of the wrapper by the lower plate 220. The bottom face of the article is now completely covered by the wrapper, the ends of which smoothly overlap as shown in Fig. 13.

As hereinbefore described, the articles are introduced into the folding chute by the feed arm 40 which ejects them from the turret 28. The folding chute is somewhat longer than the articles and the latter are 105 advanced by the feed arm until their front faces are located slightly forward of the center of the chute. The feed arm then returns into position to eject another article from the turret 28 and after the latter 110 has moved through another quarter revolution, the feed arm again operates ejecting another article from the turret 28, pushing it against the article in the folding chute and causing the latter to advance therein until 115 its forward end is introduced between the heater plates 48 while its rear end remains in the folding chute. The article thus positioned partly in the chute and partly between the heater plates fails to reach the turret 120 44. Upon the next forward stroke of the feed arm 40, however said article is advanced into that pocket 100 of the turret 44 which is then at rest at the receiving station 46.

The overlapping wrapper ends at the bottom of the article are sealed while the article is in the folding chute. To this end, the lower plate 220 of the folding chute is heated so that the wax in the overlapping ends 125 of the wrapper will be melted to cause said 130

ends to adhere to each other. For the purpose of heating the lower plate 220, an electric heating unit 266 (Figs. 1 and 3) may be removably inserted in a recessed enlargement at the delivery end of the plate 220.

As the article approaches the delivery end of the folding chute the bottom portions *e* of the tubular wrapper extensions at opposite sides of the article are engaged by rigid 10 folding lugs 268 on the lower plate 220 (Figs. 18 and 19) and these folding lugs raise said wrapper extensions *e* toward the end faces of the article, but do not fold them closely against said faces, the wrapper extensions being raised to the angular positions indicated in Fig. 19. The side members 224 of the folding chute are undercut, as shown at 270 in Fig. 18, to permit the above described preliminary folding of the 20 wrapper extensions *e*.

The heater plates 48 are somewhat longer than the articles and are provided with smooth, vertical, inwardly directed faces for engaging the bottom portions *e* of the tubular wrapper extension, which portions have already been partially folded as described, and completing the folding of these extensions by pressing them tightly against the opposite ends of the article. In order 25 that the heater plates 48 shall thus press the wrapper extensions against the ends of the articles and shall also be capable of accommodating between them, articles varying from one another somewhat in size, the heater plates are mounted in a manner similar to the manner of mounting of the side members 224 of the folding chute.

As best shown in Fig. 4, the heater plates 48 are mounted upon the upper ends of tubular arms 272 within which are located electric heating units 274. The arms 272 are pivotally mounted for tilting adjustment upon the horizontal pivot rods 256 which extend from the bracket arm 230 to support 40 them. The arms 272 are extended below the pivot rods 256 and apertured to receive the opposite ends of a rod 276 the central portion of which is fixed in the web 228. The heater plates 48 are pressed yieldingly toward each other by springs 278 which surround the rod 276 on opposite sides of said 45 web, said springs bearing against the web and against the downward extensions of the arms 272. The inward movement of the heater plates is limited by means of nuts 280 threaded upon the ends of the rods 276 and engaging the extensions of the arms 272. The nuts 280 are so adjusted that the heater plates 48 will be spread apart somewhat by 50 the introduction between them of an article of the smallest size supplied to the machine, and consequently the spring 276 will be compressed so that the heater plates will be yieldingly held against the ends of the article as 55 described. The partially folded portions *e*

of the wrapper extensions are folded flat against the opposite sides of the articles as the latter passes between the heater plates by means of folding faces 282 at the ends of said plates nearer the folding chute. The 70 heat from the heating units 274 causes the portions *e* to adhere to the previously folded portions *c* and *d*.

The upper portions *f* of the tubular side extensions of the wrapper are not folded as 75 the article is advanced between the heater plates 48, and said portions, which project beyond the ends of the article as clearly shown in Fig. 16, are received in deep channels 284 in the inner faces of the heater 80 plates, these channels being open at both ends of the plates. It is essential for the upper portions *f* of the wrapper extensions to enter the channels 284, since these channels are to function in the subsequent folding of said wrapper portions as will later appear, and such entrance is insured by a certain feature in the construction and arrangement of the upper plate 222 of the folding chute, namely, the unyielding mounting 90 of this plate at the discharge end of the chute in such a horizontal plane as to guide said wrapper extensions into said channels. It will be seen that the lower plate 220 yields downwardly at this end of the chute to accommodate articles of different thicknesses while the upper plate 222 remains stationary and consequently the upper wrapper extensions are always located in alignment with the channels 284 irrespective of variations 100 in the thickness of the articles operated upon.

The final step in the wrapping operation consists in folding the portions *f* of the side extensions of the wrapper against the ends of the article. This operation takes place as the turret 44 starts to rotate after an article has been fed into the pocket 100 at the receiving station 46. The movement of the turret pulls the extending wrapper portions 110 *f* from the channels 284 and the flat inner faces of the heater plates 48 above said channels wipe the portions *f* against the end faces of the article and seal said portions to the portions previously folded over said ends 115 of the article.

The article has now been completely wrapped and sealed, and the present invention contemplates the cooling of the sealed portions of the wrapper before the article 120 is discharged from the turret 44 to obviate any tendency of portions of the wrapper to become unfolded and thereby insure that the articles will be delivered from the machine in a permanently wrapped and sealed 125 condition. With this end in view the cooling device 50 is provided, said device comprising segmental plates which engage the wrapped and sealed end faces of the articles as the latter pass from the receiving station 130

46 to the delivery station 52 and operating to extract heat from the sealed wrapper portions while holding said portions under yielding pressure during the setting or hardening of the wax at the sealed joints.

As shown in Figs. 5 and 6, a single segmental cooling plate 290 is provided for engaging the end faces of the articles which are directed toward the front side frame 60. 10 This cooling plate 290 is rigidly secured to said side frame and is shaped to completely cover the end faces of the articles throughout substantially the entire course of their travel from the receiving station 46 to the 15 delivery station 52. The plate 290 is so located as to provide a slight clearance between itself and the turret 44. The opposite end faces of the articles are engaged by a segmental cooling plate that is constructed 20 in two separated sections 292 and 294, said sections being arranged in butting end-to-end relation and carried by a curved arm 296 which is mounted for horizontal swinging movement about a pivot stud 298, the 25 latter being carried by a lug 300 on the front frame member 60. Normally the arm 296 is locked in parallel relation with the stationary cooling plate 290 so as to locate the plates 292 and 294 for engagement with 30 the articles. To thus lock the plate 296 in its operative position a latch pin 302 is mounted for vertical sliding movement in guiding lugs projecting from said arm and the lower end of said pin is adapted to enter 35 a hole in the lug 300. The latch pin is provided with a head by means of which it may be readily withdrawn from the hole in the lug 300, thereby unlocking the arm 296 so that the cooling plate sections 292 and 294 40 may be swung away from the stationary plate 290 to permit the removal from the turret 44 of any articles which may have become jammed therein. A handle 304 is provided to facilitate the manipulation of the 45 supporting arm 296.

Each of the cooling plate sections 292 and 294 are supported by a plurality of studs 306 which project at right angles to said plate sections and extend through apertures in the supporting arm 296. Springs 50 308 are coiled around the studs 306 between the arm 296 and the plate sections 292 and 294 and press said sections toward the stationary plate 290. The extent of movement 55 of the plate sections 292 and 294 under the influence of the springs 308 is limited by suitable cotter pins 310 in the studs which engage the outer side of the arm 296 and are located so as to normally maintain said 60 plate sections 292 and 294 parallel to the stationary plate 290 and spaced from the turret 44 to provide a slight clearance space between said turret and plate sections. To 65 increase the capacity of the plate sections 292 and 294 to extract heat from the wrap-

pers, each of said sections is provided with a series of heat-radiating fins or vanes 311 which facilitate the radiation of heat from the plate sections. Both plate sections 292 and 294 flare outwardly at the ends first engaged by the articles, one of said flaring portions being indicated at 312 in Fig. 6. In this way the articles are enabled to easily force their way behind said plate sections. The above described yielding mounting of the cooling plate sections 292 and 294 obviously enables them to adjust themselves to the articles of different widths in the turret 44. The yielding cooling member is made in two sections, as described, and each section is made of such length that no more than two articles may engage either of said sections at the same time. This construction eliminates the possibility of one or more articles failing to be engaged by the cooling plate by reason of the presence both before and behind said articles of other articles of somewhat greater width. In the present construction, the apertures in the arm 296, through which the studs 306 extend are 70 large enough to permit a slight tilting of said studs and if either plate section 292 or 294 simultaneously engages two articles of different sizes the plate sections will tilt slightly so as to engage each article and 75 press each article with equal force.

It will be seen by reference to Fig. 6 that the turret 44 is slightly narrower than the articles operated upon so that the latter will project beyond opposite sides of the 80 turret to insure their engagement with the cooling plate. The amount of clearance between the turret 44 and the stationary cooling plate is very small and when an article of minimum size, such as the article shown at 314 in Fig. 6, are being acted upon substantially the same amount of clearance will be present between the turret and the yielding cooling plate sections. It is obvious, however, that when a larger article is being acted upon the yielding plate section engaged thereby will be forced farther away from the side of the turret so that the clearance space between the turret and the yielding plate section will be increased. Such a condition is illustrated in Fig. 6 wherein a 85 relatively large article 316 is in engagement with the plate section 294 and the clearance space between said section and the turret is greater than the clearance space between the other plate section 292 and the turret. If there is more than minimum amount of clearance space between the turret and the yielding cooling plate sections there is a 90 possibility that the drag exerted by said plate sections upon the folded over wrapper extensions at the ends of the articles will draw into the clearance space behind the article, the portion of the wrapper which is folded about the rear corners of the side 95 100

faces engaged by said plate sections and as a result there will be an undesirable fullness in the wrappers where the same has been pulled away from the corners of the articles. 5 To prevent the occurrence of the above described undesirable condition, the walls of the pockets 100 are provided, along their radial edges, with prongs 320 (Fig. 5) which extend in the planes of said side walls and 10 are arranged to register with grooves 322 in the yielding plate sections, said grooves being concentric with the axis of rotation of the turret 44. The prongs 320 are of such length as to bridge across the clearance 15 space between the turret and the yielding cooling plate sections irrespective of variations in the size of the articles being wrapped. To permit the prongs to pass the heater plates 48, the latter are provided with 20 suitable slots 324 (Fig. 2) to receive said prongs.

When the articles have been advanced beyond the cooling device 50 by the rotation of the turret 44, the sealed portions of the 25 wrappers have hardened or set so that there is no danger that they will accidentally open up during subsequent handling and shipping of the articles. Immediately after pausing beyond the cooling device 50 the 30 articles are brought to the delivery station 52 where they are discharged from the turret 44 by the action of the push bar 54. As shown, a platform 326 is provided for receiving the articles as they are ejected from 35 the turret 44 and suitable provision may be made removing the articles from the platform if desired.

The invention has been disclosed herein, for illustrative purposes, in what is now considered its preferred embodiment, but the scope of the invention is defined by the appended claims rather than by the foregoing description.

What I claim is:

45 1. In a wrapping machine, means for applying a wrapper to an article of rectangular prismatic form to cover four sides of the article and to provide a tubular wrapper extension projecting beyond the two ends 50 of the article, said means including a folding chute for yieldingly pressing the wrapper against two of said sides after it has been folded thereover, means for engaging the portions of the wrapper extending beyond two opposite edges of the uncovered ends and folding said extensions against 55 said ends leaving two unfolded wrapper extensions still projecting beyond the article, means rigid with the folding chute for 60 starting the folding of one of the remaining unfolded extensions at each end of the article, independent means for completing said folding operation and yieldingly pressing said extensions against the article, and 65 means for folding the remaining wrapper

extensions to complete the wrapping of the article.

2. In a wrapping machine, a folding chute having top, bottom and side members mounted for outward yielding movement to 70 accommodate articles of varying sizes, means for applying wrappers to variable sized articles of rectangular prismatic form to cover four faces of each article and to provide tubular extensions projecting beyond the other two faces thereof and for finally positioning said article opposite the receiving end of the folding chute with said tubular extensions projecting at right angles to the length of the chute, a feed arm for 75 engaging the rear face of the article and advancing it into the chute, spaced members on said arm for folding the rear of said tubular extensions against the ends of the articles, means on the side members of 80 the chute for folding the front of said tubular extensions against the ends of the articles as they are introduced therein means on the bottom member of the chute for initiating the folding of the bottom of said 85 tubular extension against the sides of the articles as the articles are ejected from the chute by the introduction of a new article therein, and means for receiving the articles as they leave the chute and completing the 90 wrapping operation.

3. In a wrapping machine, a folding chute comprising four side members arranged to operate upon four sides of an article of rectangular prismatic form, said 100 sides being covered by a wrapper and said wrapper having tubular extensions projecting beyond the two uncovered ends of the article, each of the four side members of the chute having supporting means with provision for independent outward yielding movement of said side members to adapt the chute to accommodate articles of different sizes, the means for supporting one of said side members being constructed and 110 arranged to enable the latter to be removed at will from operative relation with the other members of the chute to permit convenient access to the interior thereof.

4. In a wrapping machine, the combination of a carrier rotatable through receiving and delivery stations and having a plurality of pockets for holding wrapped articles with their opposite ends projecting beyond the sides of the carrier, means for 115 introducing partially wrapped articles into said pockets as the latter successively reach the receiving station, heated members adjacent opposite sides of the carrier for engaging the projecting ends of the articles 120 and having slotted folding portions to receive extensions of the wrapper and fold the same against the ends of the article as the carrier rotates and for heat sealing said folded wrapper extensions.

5. In a wrapping machine, the combination of a carrier rotatable through receiving and delivery stations and having a plurality of pockets for holding wrapped articles with their opposite ends projecting beyond the sides of the carrier, means for introducing partially wrapped articles into said pockets as the latter successively reach the receiving station, a folding chute adapted to receive incompletely wrapped articles having wrapper extensions projecting beyond the front, top and bottom faces of the articles at opposite sides of the latter and to partially fold the wrapper extensions which project beyond said bottom faces against the sides of the articles, means for advancing the articles through the folding chute and introducing them into the pockets of the carrier as the latter successively reach the receiving station, heat-sealing devices adjacent opposite sides of the carrier for engaging the projecting ends of the articles said devices being constructed and arranged to complete the folding of said lower wrapper extensions as the articles are being introduced therein and subsequently to heat-seal said extensions, and said devices being provided with channels for receiving the projecting upper wrapper extensions and being operative to fold the latter against said lower extensions as the carrier rotates and to subsequently heat seal said extensions, and means for ejecting the wrapped and sealed articles from the carrier.
6. In a wrapping machine, a turret rotatable through article receiving and delivery stations and provided with a pocket adapted to receive a wrapped article having portions of the wrapper overlapping at opposite ends thereof and to hold the article with said ends projecting beyond the sides of the turret, means for heating said projecting ends of the article to seal the overlapping portions of the wrapper, a cooling plate rigidly supported at one side of the turret for engaging one of the projecting ends of the article as it leaves said heating means, and a second cooling plate at the opposite side of the turret for engaging the other projecting end of the article as it leaves the receiving station, said second plate being adapted to yield to accommodate itself to articles of different sizes and having a groove in its inner face concentric with the axis of rotation of the turret, and a projection upon the rear wall of said pocket adapted to extend into said groove to bridge across the clearance space between the turret and the yielding cooling plate.
7. In a wrapping machine, a turret rotatable through article receiving and delivery stations and provided with a pocket adapted to receive a wrapped article having portions of the wrapper overlapping at opposite ends thereof and to hold the article with said ends projecting beyond the sides of the turret, means for introducing the article into said pocket, means for heating said projecting ends of the article to seal the overlapping portions of the wrapper, a cool-

ing plate rigidly supported at one side of the turret for engaging one of the projecting ends of the article as it leaves said heating means, and inwardly spring-pressed cooling plate at the opposite side of the turret for engaging the other projecting end of the article as it leaves the receiving station and cooperating with the other cooling plate to hold the article under pressure during the cooling thereof, said latter plate being movable to a position out of cooperative relation with the rigid cooling plate.

8. In a wrapping machine, a turret rotatable through article receiving and delivery stations and provided with a pocket adapted to receive a wrapped article having portions of the wrapper overlapping at opposite ends thereof and to hold the article with said ends projecting beyond the sides of the turret, means for introducing the article into said pocket, means for heating said projecting ends of the article to seal the overlapping portions of the wrapper, a cooling plate rigidly supported at one side of the turret for engaging one of the projecting ends of the article as it leaves said heating means, a second cooling plate at the opposite side of the turret for engaging the other projecting end of the article as it leaves the receiving station, said second plate being adapted to yield to accommodate itself to articles of different sizes and having a groove in its inner face concentric with the axis of rotation of the turret, and a projection upon the rear wall of said pocket adapted to extend into said groove to bridge across the clearance space between the turret and the yielding cooling plate.

9. In a wrapping machine, a turret rotatable through article receiving and delivery stations and provided with a plurality of spaced peripheral pockets adapted to receive wrapped articles having portions of the wrapper overlapping at opposite ends thereof and to hold the articles with said ends projecting beyond the sides of the turret, means for introducing the articles into said pockets as the latter successively reach the receiving station, means at the receiving station for applying heat to said projecting ends of the article to seal the overlapping portions of the wrapper, a cooling plate rigidly supported at one side of the turret for engaging one of the projecting ends of the articles as they are advanced toward the delivery station, and a plurality of separated plate sections upon the opposite side of the turret for yieldingly engaging the other projecting ends of the articles to hold said overlapping wrapper portions in place and to extract heat therefrom, said plate sections being incapable of simultaneous engagement with more than two articles and being mounted with provision for slight angular movement to enable them to simul-

taneously engage two articles of different sizes.

10. In a wrapping machine, a turret rotatable through article receiving and delivery stations and provided with a plurality of spaced peripheral pockets adapted to receive wrapped articles having portions of the wrapper overlapping at opposite ends thereof and to hold the articles with said ends projecting beyond the sides of the turret, means for introducing the articles into said pockets as the latter successively reach the receiving station, means at the receiving station for applying heat to said projecting ends of the article to seal the overlapping portions of the wrapper, a cooling plate rigidly supported at one side of the turret for engaging one of the projecting ends of the articles as they are advanced toward the delivery station, a movable support at the opposite side of said turret, a plurality of segmental cooling plates arranged end to end and yieldingly mounted upon said support, and means for latching said support 25 in position to enable said segmental plates to yieldingly engage the other projecting ends of the articles to hold said overlapping wrapper portions in place during the cooling thereof and for releasing said support to 30 enable the segmental plates to be moved out of operative positions.

11. In a wrapping machine, a rotatable turret provided with a pocket having a rigid wall and a yielding wall for engaging upper and lower sides of a partially wrapped rectangular article to hold same in said pocket, means for rotating the turret to transfer the article from a receiving to a delivery station, a folding chute adjacent the delivery station for receiving said article, the chute having upper and lower disposed plates one of which is arranged to engage the side of the article previously engaged by the yielding wall of said pocket and being mounted 40 with provision for yielding movement at the end adjacent the entrance to said chute and pivotally mounted upon a stationary part of the machine at its opposite end, while the other of said plates is arranged to engage the end of the article previously engaged by the rigid wall of said pocket and being pivotally mounted upon a stationary part of the machine at the end adjacent the entrance to said chute and mounted at its opposite 50 end with provision for outward yielding movement.

12. In a wrapping machine, means for completing the wrapping of a rectangular prismatic article four faces of which are covered by a wrapper having substantially tubular extensions projecting beyond the ends of the article said means including a plate for applying yielding pressure to one of the covered faces of the article, means for advancing the article across said plate, rigid

means on said plate for engaging the portions of said tubular wrapper extensions projecting beyond the face engaged by said plate and folding said portions part way toward the uncovered ends of the article, 70 inwardly pressed members for engaging said partially folded wrapper portions and completing the folding thereof against said uncovered ends of the article, and means for folding the remaining projecting portions 75 of the wrapper to complete the wrapping of the article.

13. In a wrapping machine, means for covering four faces of an article of rectangular prismatic form with a wrapper having tubular extensions projecting beyond the two ends of the article, means for maintaining the four covered faces under yielding pressure during subsequent operations for covering the ends of the article, means for engaging the portions of said tubular extensions at the rear side thereof and means for engaging portions of said tubular extensions at the front side thereof, both of said means acting to fold its respective portions of the wrapper against the uncovered ends of the article leaving two unfolded wrapper extensions projecting beyond said ends, means for engaging one of said unfolded extensions at each end of the article 95 and folding said extensions toward the article but not into contact therewith, means for engaging said partially folded extensions to complete the folding thereof by pressing them yieldingly against the ends of the article, and means for folding the remaining wrapper extensions to complete the wrapping of the article. 100

14. In a wrapping machine having means for applying to a rectangular prismatic article a wrapper covering the top, bottom, front and rear faces of the article and having substantially tubular extensions projecting beyond the ends thereof, means for subsequently operating upon the article to complete the wrapping thereof including a folding chute having inwardly pressed opposed walls for yieldingly engaging the top and bottom covered faces of the article, means for engaging the portions of the tubular extensions projecting beyond the rear face at the ends of the article and folding them against said ends and for feeding the article through the chute, means on the chute for engaging the portions of the tubular 115 extensions projecting beyond the front covered face of the article and folding them against the ends of the article, rigid means on one of said inwardly pressed walls of the chute for engaging the portions of the 120 wrapper projecting beyond the face of the article engaged by said wall and folding said portions part way toward the ends of the article as the latter is advanced through the chute, means in advance of the chute for 125 advancing the article across said plate, rigid

yieldingly engaging said partially folded wrapper portions and completing the folding thereof against said ends, and means for folding the remaining projecting portions of the wrapper to complete the wrapping of the article.

15. In a wrapping machine for rectangular prismatic articles, a wrapping wheel having pockets rotatable through receiving and delivery stations, means for introducing an article and wrapper into a pocket at its receiving station to partially fold the wrapper about the sides of the article, a folding chute at the delivery station of said pockets and means to discharge the partially wrapped article into said chute to complete the folding of the wrapper about the sides of the article and leaving extensions beyond the ends of the article, 20 said folding chute comprising devices for tucking one side of said extensions of said wrapper, and slotted portions to initiate end folds of said extensions, a finishing wheel having pockets rotatable through receiving and discharging stations and adapted to receive the partially wrapped article from said chute, heat sealing and folding devices adjacent the receiving station of said finishing wheel pockets and arranged 25 to complete the end fold initiated in said chute, said heat sealing and folding devices also comprising slotted portions to make final overlapping end folds of said wrapper when the pocket of the finishing wheel carries the article from the receiving station.

16. In a wrapping machine for rectangular prismatic articles, a wrapping wheel having pockets rotatable through receiving and delivery stations, means for introducing an article and wrapper into a pocket at its receiving station to partially fold the wrapper about the sides of the article, a folding chute at the delivery station of said pockets and means to discharge the partially wrapped article into said chute to complete the folding of the wrapper about the sides of the article and leaving extensions beyond the ends of the article, 40 said folding chute comprising devices for tucking one side of said extensions of said wrapper, and slotted portions to initiate end folds of said extensions, a finishing wheel having pockets rotatable through receiving and discharging stations and adapted to receive the partially wrapped article from said chute, heat sealing and folding devices adjacent the receiving station of said finishing wheel pockets and arranged to complete the end fold initiated in said chute, said heat sealing and folding devices also comprising slotted portions to make final overlapping end folds of said wrapper when the pocket of the finishing wheel carries the article from the receiving station.

wheel having pockets rotatable through receiving and discharging stations and adapted to receive the partially wrapped article from said chute, heat sealing and folding devices adjacent the receiving station of said finishing wheel pockets and arranged to complete the end fold initiated in said chute, said heat sealing and folding devices also comprising slotted portions to make final overlapping end folds of said wrapper when the pocket of the finishing wheel carries the article from the receiving station, cooling plates at each side of said finishing wheel and arranged to effect yielding pressure upon the wrapped ends of said articles during the passage of the latter to the delivery station.

17. In a wrapping machine for rectangular prismatic articles, a wrapping wheel having pockets rotatable through receiving and delivery stations, means for introducing an article and wrapper into a pocket at its receiving station to partially fold the wrapper about the sides of the article, a folding chute at the delivery station of said pockets, an ejector to discharge partially wrapped articles into said chute to complete the folding of the wrapper about the sides of an article and leaving extensions of the wrapper beyond the ends of the wrapper, said ejector having tucking elements to tuck one side of said extensions, said folding chute comprising devices for tucking the other side of said extensions of said wrapper, and slotted portions to initiate end folds of said extensions, a finishing wheel having pockets rotatable through receiving and discharging stations and adapted to receive the partially wrapped article from said chute, heat sealing and folding devices adjacent the receiving station of said finishing wheel pockets and arranged to complete the end fold initiated in said chute, said heat sealing and folding devices also comprising slotted portions to make final overlapping end folds of said wrapper when the pocket of the finishing wheel carries the article from the receiving station.

In testimony whereof I have affixed my signature.

ELMER LOVELL SMITH.
